US0D1062603S

(12) **United States Design Patent** (10) **Patent No.:** **US D1,062,603 S**
(45) **Date of Patent:** **** Feb. 18, 2025**

(54) **COMBINED RECHARGEABLE PORTABLE POWER SUPPLY AND AIR COMPRESSOR**

(71) Applicant: **Shenzhen Grepow Battery Co., Ltd,**
Shenzhen (CN)

(72) Inventors: **Bing Liu**, Shenzhen (CN); **Miao Liu**,
Shenzhen (CN)

(73) Assignee: **Shenzhen Grepow Battery Co., Ltd,**
Shenzhen (CN)

(**) Term: **15 Years**

(21) Appl. No.: **29/893,945**

(22) Filed: **Jun. 5, 2023**

(30) **Foreign Application Priority Data**

Mar. 7, 2023 (CN) 202330096939.2

(57) **CLAIM**

The ornamental design for a combined rechargeable portable power supply and air compressor as shown and described.

DESCRIPTION

FIG. 1 is a front, left and bottom perspective view of a combined rechargeable portable power supply and air compressor, showing our new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the combined rechargeable portable power supply and air compressor that form no part of the claimed design.

1 Claim, 8 Drawing Sheets
